UNITED STATES PATENT OFFICE

HERBERT T. FOGG, OF EAST ORANGE, NEW JERSEY, ASSIGNOR TO NATIONAL BISCUIT COMPANY, OF NEW YORK, N. Y., A CORPORATION OF NEW JERSEY

COMBINATION DISPLAY AND SHIPPING CONTAINER

Application filed February 19, 1929. Serial No. 341,223.

This invention relates to folding boxes, and more particularly, to foldable display boxes of the kind usually made from pasteboard, and to methods of using the same for 5 packaging and shipping purposes.

A general object of the invention is to provide a display container which, when not in use, may be folded flat within a small compass and which is made from a blank so 10 formed as to allow a maximum number thereof to be cut from a given quantity of sheet material, while at the same time the box, when formed, will have a sturdy construction and will display the contents in a most 15 efficient and attractive manner.

Another object is to provide a display box having a foldable display flap which is 20 swingingly connected to the main body portion of the display box in a manner such that it is supported in proper display position when swung rearwardly, but may be readily folded forwardly over the contents of the 25 box.

A still further object is to provide a novel 25 manner of packaging boxed goods utilizing the improved box as a packing box for shipping boxed materials, such as cakes and the like.

Other objects of the invention will in part 30 be obvious and will in part appear herein-after.

The invention accordingly comprises an article of manufacture possessing the features, properties, and the relation of elements 35 which will be exemplified in the article hereinafter described and the scope of the application of which will be indicated in the claims.

For a fuller understanding of the nature 40 and objects of the invention reference should be had to the following detailed description taken in connection with the accompanying drawings, in which:

Figure 1 is a front elevation of one exemplification of the invention in display position;

Fig. 2 is an end view of Fig. 1;

Fig. 3 is a view similar to Fig. 2, but showing the device in shipping position with the 50 boxed goods therein;

Fig. 4 is a view of the blank by the folding of which the device shown in Fig. 1 is formed;

Fig. 5 is a detail plan view of the display flap hinge and supporting means shown in Fig. 1; and

Fig. 6 is a detail sectional view taken along the dotted lines 6—6 of Fig. 5 looking in the direction of the arrows.

By more particular reference to the drawings it will be seen that the exemplification of the invention shown therein is made of semi-rigid material such as cardboard and comprises a bottom wall 10, triangular side walls 11 and 12, a rear wall 13 and a display flap 14 swingingly mounted on the top of said rear wall.

Positioned behind said rear wall 13, and acting as a support therefor, is a supporting wall 15, which is formed from the members 16 and 17, which overlap each other and are held together by co-operating means such as the tongue-and-slit 18 and 19. As shown in Fig. 4 and by dotted lines in Fig. 1, the members 16 and 17 are preferably unsymmetrical 75 formed as to length with respect to the main body portions of the device so that the tongue-and-slit connection comes adjacent the bend between the member 17 and the end wall 12. Such a construction not only provides 80 a secure connection between the members 16 and 17, but also allows a maximum number of blanks to be cut from a given amount of sheet material.

It will be understood, of course, that, as is 85 usual, score marks are made on the blank at each place the elements of the box are to be bent with respect to each other. With the exception of the score mark 20 between the rear wall 13 and the display flap 14, these 90 score marks are continuous. The score mark 20, however, is interrupted in at least one place, and across the interrupted portion an offset score mark 21 is formed. Also, between the ends of the score marks 20 and 21 95 there are provided transverse slits 22. Such a construction—as will be seen particularly by reference to Figs. 5 and 6—while allowing the display flap 14 to be readily swung forwardly or rearwardly with respect to the 100

back 13, holds or supports the display flap 14, when in its rearward position, at an appropriate angle, thereby avoiding the complicated mechanisms which have heretofore been deemed necessary to accomplish such supporting action.

Although only one offset score line portion has been shown in the drawings, it will be readily understood that a plurality thereof may be used, if desired, it being preferable, of course, in such case that such interruption should be more or less symmetrical disposed laterally with respect to the score line 20. That portion of the material from which the article is made which lies between the transverse slits 22, acts as a hinge, and also acts to limit the swing of the display flap 14 with respect to the rear wall 13.

As will be seen by reference to Fig. 3, the display flap 14 is of substantially the same configuration and size as that of the bottom wall 10 whereby, when boxed goods such as cakes are stacked therein, the display flap 14 may be folded forwardly and the contents secured in position merely by running a string 23 or a sheet of wrapping paper 24, or both, around the ensemble, the ends of the paper being folded in the usual manner. This provides a novel manner of packaging wrapped goods for shipment in which the packaging is accomplished quickly and easily and with a large saving of material. When packed for shipment the display box forms a partial wrapper and the wrapping paper or string completes the wrapping securing the boxed goods in place and when broken comes off without injuring or disturbing the display box or its contents.

Furthermore, with the improved display box as the boxed goods are removed the remainder can be rearranged on the bottom wall 10, so that at all times, by reason of the triangular form of the end walls 11 and 12, there is provided an attractive and efficient display of the contents of the device.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A device of the class described, comprising, in combination, a bottom wall, a rear wall, means for supporting the rear wall in

vertical position, a display flap forming a continuation of said rear wall and swingingly connected thereto at certain portions by a score line; another portion of said connection having a score line offset from said first-mentioned score line, and a transverse slit interrupting said connection between said score lines.

2. A device of the class described, comprising, in combination, a bottom wall, a rear wall, means for supporting the rear wall in vertical position, a display flap forming a continuation of said rear wall and swingingly connected thereto at certain portions by a score line; said score line being interrupted at another portion of the connection between the rear wall and the display flap by a pair of transversely-disposed slits, the portion of said connection positioned between said slits having a score line offset with respect to said first-mentioned score line.

3. A device of the class described, comprising, in combination, a bottom wall, a vertically-disposed rear wall, triangularly-shaped end walls, each of said end walls at its rear side having a flap connected thereto by a score line and adapted to be bent to a position behind said rear wall; said flaps having a cooperating tongue-and-slit for securing them in said last-mentioned position, said triangular end walls forming a substantially straight line from the front edge of the bottom wall to the top edge of the rear wall; and a display flap swingingly connected to the top edge of said rear wall and adapted to swing forwardly with respect thereto; said display flap being of substantially the same dimensions as the bottom wall.

4. A device of the class described, comprising, in combination, a bottom wall, a vertically-disposed rear wall, triangularly-shaped end walls, each of said end walls at its rear side having a flap connected by a score line and adapted to be bent to a position behind said rear wall; said flaps having a cooperating tongue-and-slit for securing them in said last-mentioned position, said triangular end walls forming a substantially straight line from the front edge of the bottom wall to the top edge of the rear wall; one of said flaps being of substantially the same length as the rear wall, and the tongue-and-slit connection between said flaps being positioned adjacent the bend between the other flap and its end wall.

5. A blank for forming a foldable display box, comprising three rectangular portions joined laterally and defined laterally with respect to each other by score lines, the first of said rectangular portions having connected thereto at each of its ends a triangular section defined with respect thereto by a score line, the hypotenuse of said triangular sections being directed away from the ends of said first rectangular section at an

angle such that at the intersection thereof with the score line between said first and second rectangular sections the height of the triangle is approximately equal to the lateral dimension of said second-mentioned rectangular section; each of said triangular sections on said last-mentioned side having a flap extending therefrom and defined with respect thereto by a score line; said flaps being adapted to be folded behind said second-mentioned section to support the same at right angles to said first-mentioned rectangular section; said flaps having cooperating means holding each other in position, the score line between said second- and third-mentioned rectangular sections being interrupted by an offset score line defined by transverse slits.

6. A blank for forming a foldable display box, comprising three rectangular portions joined laterally and defined laterally with respect to each other by score lines, the first of said rectangular portions having connected thereto at each of its ends a triangular section defined with respect thereto by a score line, the hypotenuse of said triangular sections being directed away from the ends of said first rectangular section at an angle such that at the intersection thereof with the score line between said first and second rectangular sections the height of the triangle is approximately equal to the lateral dimension of said second-mentioned rectangular section; each of said triangular sections on said last-mentioned side having a flap extending therefrom and defined with respect thereto by a score line; said flaps being adapted to be folded behind said second-mentioned section to support the same at right angles to said first-mentioned rectangular section; said flaps having cooperating means holding each other in position, the score line between said second- and third-mentioned rectangular sections being interrupted by an offset score line defined by transverse slits; the third-mentioned rectangular section being of substantially the same dimensions as the first-mentioned rectangular section.

59 7. A blank for forming a foldable display box, comprising three rectangular portions joined laterally and defined laterally with respect to each other by score lines, the first of said rectangular portions having connected thereto at each of its ends a triangular section defined with respect thereto by a score line, the hypotenuse of said triangular sections being directed away from the ends of said first rectangular section at an angle such that at the intersection thereof with the score line between said first and second rectangular sections the height of the triangle is approximately equal to the lateral dimension of said second-mentioned rectangular section; each of said triangular sections on said last-

mentioned side having a flap extending therefrom and defined with respect thereto by a score line; said flaps being of unequal length and being adapted to be folded behind said second-mentioned section to support the same at right angles to said first-mentioned rectangular section; said flaps having cooperating means holding each other in position, the score line between said second- and third-mentioned rectangular sections being interrupted by an offset score line defined by transverse slits.

In testimony whereof I affix my signature.

HERBERT T. FOGG.
